UNITED STATES PATENT OFFICE.

SHIZUO SATO, OF OSAKO-SHI, JAPAN.

STETHOSCOPE.

Application filed July 9, 1925. Serial No. 42,557.

My invention relates to stethoscopes and more particularly to those, in the class specified, having a sound collector with two forked legs, to which flexible rubber tubes 5 are respectively secured in order to enable the sound to be transmitted through themselves to the ears of the auscultator or the doctor.

In the preferred embodiment of my invention, the stethoscope comprises a pair of nipples or ear pieces, a pair of rubber tubes, a sound collector and an elastic ball member, which last two members constitute the novel features of my invention.

An object of my invention is to provide a stethoscope of which the open trumpet end of the sound collector can be readily and firmly caused to adhere to the part to be tested in order to obtain a clear and correct 20 test or auscultation.

Another object of my invention is to provide a stethoscope of which the several parts are readily taken apart for repairing or cleaning.

A further object of my invention is to provide means whereby the stethoscope may be readily applied to or removed from the part to be auscultated.

Other objects and advantages of my invention will be fully understood, together with its construction and features, by reference to the following detailed description and the accompanying drawings, wherein:—

Fig. 1 is a perspective view of a complete 35 stethoscope embodying my invention.

Fig. 2 is an underside view of the sound collector of the embodiment shown in Fig. 1.

Fig. 3 is a sectional elevation of the sound collector and a portion of its continuation 40 taken on the line III—III of Fig. 2.

Fig. 4 shows a detailed section of a part of the sound collector.

Referring now to the drawings, the embodiment comprises a tubular or hollow 45 sound collector S, having a forked end member C, each leg of which is provided with a passage therethrough and continued by a rubber tube 6 ending by a nipple 5. The sound collector S, comprises a bell or bowl-shaped end member A, having a bell or trumpet-shaped middle opening 1' formed and surrounded by a flange 1 and continued by the forked passages of the member C, and also having an outer annular flange 7, provided with an annular recess 8 which sur-

rounds the flange 1. A plurality of ports 2 are provided and arranged in an annular series in the bowl and opening into the annular recess 8 between the flanges 1 and 7. The member A has a central hollow extension 3 having screw threads on its outer cylindrical surface. The sound collector S also comprises a coupler or tubular portion B adapted to receive the extension 3, when screwed therein. The coupler B has an annular extension 65 or enlargement provided with a plurality of ports 4, designed and arranged to register with the ports 2, forming a plurality of continued communications 2—4.

The coupler B also receives the screw 70 threaded end 9 of the forked end member C.

An elastic ball member D, such as of rubber or like material, has two openings or cuts, adapted to allow the collector S to be passed therethrough as shown in Fig. 3. 75 The diameters of said openings are such that their edges may respectively fit the outer periphery of the hollow extension 9 of the member C and an annular groove 10 in the upper annular surface of the body of the member A. By this arrangement, the ball D can be secured to and partly enclose the sound collector, the edge of one of the openings being inserted and secured between the end of the member B and the corresponding 80 shoulder of the members C and A.

In using the stethoscope above illustrated, the ball D is grasped to expel the air therein through the ports 4 and 2, before the sound collector is applied to the part to be auscultated, and released after the sound collector is applied with its bowl-shaped member A contacting with the part to which the stethoscope is applied. On release of the ball D, suction will be produced on the expansion 95 of the ball and the cup will adhere to the part to which it has been applied, without the necessity of grasping the flexible or rubber tubes 6 in order to secure an adhesion of the sound collector to the part. Moreover the adhesion of the sound collector is very strong, and it is not necessary to hold the device in place. An extremely clear and pure auscultation of sounds will be obtained, without any external noises.

In this way very correct and clear auscultation of murmurs of embryos, mixed sounds of wombs or placenta, murmurs of patients in a syncopic or dying condition, etc. will be obtained.

To detach the stethoscope the ball D is squeezed whereupon the device can be removed without difficulty.

Though I have disclosed only one embodiment of my invention, it will be easily understood by those skilled in the art that various changes, modifications and substitutions can readily be made without departing from the spirit and scope of the aforesaid invention.

10 Having now particularly described and ascertained the nature of my invention and in what manner the same is to be performed, I declare that what I claim is.

15 1. A stethoscope comprising a pair of nipples, a pair of flexible tubes, a sound collector and an elastic enclosure, surrounding the body of said sound collector and with its interior in communication through a plurality of ports with a recess surrounding the 20 bell-shaped open end of said sound collector.

2. A stethoscope, comprising a pair of

nipples, a pair of rubber tubes, a sound collector and a flexible ball, said sound collector consisting of a forked end member, a bell-shaped end member and a coupler for 25 uniting said two members to form a continual passage for the sound collector, and said rubber ball substantially enclosing said coupler and having communication with an annular recess provided around the bell-shaped open end of said bell-shaped end member.

3. A stethoscope comprising means for collecting sound in a patient to be auscultated, means for providing a deformable but self-restoring enclosed space, and means for discharging air in said space through an opening arranged around but independently of the end opening of said sound collecting means.

35 In testimony whereof I affix my signature.
40 SHIZUO SATO.
